(57) **CLAIM**

The ornamental design for a vehicle front fender, as shown and described.

DESCRIPTION

FIG. 1 is a perspective view of a first embodiment vehicle front fender in accordance with the present invention, wherein a perspective view a second embodiment vehicle front fender in accordance with the present invention is a mirror image thereof;

FIG. 2 is another perspective view of the first embodiment vehicle front fender, wherein another perspective view of the second embodiment vehicle front fender is a mirror image thereof;

FIG. 3 is a right side perspective view of the first embodiment vehicle front fender, wherein a left side perspective view of the second embodiment vehicle front fender is a mirror image thereof;

FIG. 4 is another perspective view of the first embodiment vehicle front fender, wherein another perspective view of the second embodiment vehicle front fender is a mirror image thereof;

FIG. 5 is a left side elevation view of the first embodiment vehicle front fender, wherein a right side elevation view of the second embodiment vehicle front fender is a mirror image thereof; and,

FIG. 6 is a right side elevation view of the first embodiment vehicle front fender, wherein a left side elevation view of the second embodiment vehicle front fender is a mirror image thereof.
